TUMBLER LOCK

Harry F. George, Chicago, Ill.

Application June 21, 1941, Serial No. 399,123

18 Claims. (Cl. 70—363)

This invention relates to locks and more particularly to locks of the tumbler type.

Among the objects of this invention are to provide a tumbler lock that is pick-proof, economical to manufacture, one that has a key that is more difficult to duplicate and one in which it is impossible to break a key off in the lock by a turning force. Even if the key handle be broken off from the key body, the body may still be easily removed from the keyhole.

Another object is to provide a tumbler lock in which the locking cylinder may be removed from the locking mechanism body, and a new locking cylinder, having a different arrangement of tumblers, inserted in order to change the key combination when desired.

A further object is to provide a lock of the character described that eliminates any slot, depression or projection that would enable turning the cylinder for picking purposes.

A still further object is to provide a lock which cannot be frozen against unlocking operation.

Another object is to provide a tumbler lock of improved construction, of greater certainty and smoothness of operation, of greater adaptability and pleasing appearance, and of greater durability and dependable operation.

Other objects, advantages and capabilities will later more fully appear.

My invention further resides in the combination, construction and arrangement of parts illustrated in the accompanying drawings, and while I have shown therein preferred embodiments I wish it understood that the same is susceptible of modification and change without departing from the spirit of the invention.

In the drawings:

Fig. 1 is a perspective view of a movable part having my improved lock mounted therein for locking or unlocking the part as desired.

Fig. 2 is an enlarged side elevation of the locking cylinder.

Fig. 3 is an enlarged longitudinal section taken on a median plane through the locking cylinder showing a fragmentary portion of the locking mechanism body and a key partly in elevation and partly in section in a position just before being inserted into the locking cylinder.

Fig. 4 is an end elevation of the locking cylinder looking toward the right-hand end of Fig. 3.

Fig. 5 is an end elevation of the locking cylinder looking toward the left-hand end of Fig. 3 but omitting the key.

Fig. 6 is a transverse section through the locking cylinder on the line 6—6 of Fig. 3.

Fig. 7 is a transverse section through the locking cylinder on the line 7—7 of Fig. 3.

Fig. 8 is a transverse section through the locking cylinder on the line 8—8 of Fig. 3, and showing a fragmentary portion of the locking mechanism body surrounding the locking cylinder.

Fig. 9 is a transverse section through the locking cylinder on the line 9—9 of Fig. 3.

Fig. 10 is a perspective view of the key used in the locking cylinder of Figs. 1—9.

Fig. 11 is an enlarged disassembled perspective view of the locking cylinder showing certain of the parts in separated position for the sake of clarity.

Fig. 12 is an enlarged perspective view of the shell locking spring for holding the barrel against separation from the shell, but permitting such separation when desired.

Fig. 13 is a view similar to Fig. 3 but showing the key fully inserted into the locking cylinder with the parts in position to throw the locking bolt one way or the other.

Fig. 14 is an enlarged longitudinal sectional view showing the key inserted and a wire or the like pushing inwardly on the dummy pin to move it into position to clear the striking projection and permit removal of the locking cylinder when it is desired to change the lock.

Fig. 15 is an enlarged longitudinal section through a modified form of my improved lock and showing a different construction for permitting removal of the locking cylinder.

Fig. 16 is a transverse section on the line 16—16 of Fig. 15.

Fig. 17 is a view similar to Fig. 15 but showing a further modification.

Fig. 18 is a transverse section on the line 18—18 of Fig. 17.

Fig. 19 is an enlarged fragmentary perspective view of the shell in the form of lock shown in Fig. 17.

Fig. 20 is an enlarged perspective view of a spring holding means of a type for use in the shell of Figs. 17 and 19.

Fig. 21 is an enlarged perspective view of the intermediate rotatable portion and part of the plug used in connection with the parts shown in Figs. 17—20.

Fig. 22 is an enlarged perspective view of a key blank of the flat key type, provided with means that may be cut to enable it to operate in my improved tumbler lock.

Fig. 23 is a fragmentary view, in still greater enlargement, of the front end of a modified form

of a finished flat key for use in a tumbler lock embodying my invention.

Fig. 24 is an enlarged end elevation of a tumbler locking cylinder formed to be operated with a flat key of the type shown in Figs. 22 and 23, and showing the front end portion of the key inserted into the key-receiving slot.

Fig. 25 is an enlarged diagrammatic view showing the operating relationship between the forward end portion of a flat key of the type shown in Figs. 22 to 24, and the front end of the tumblers.

Fig. 26 is a side elevation illustrating one of various types of shouldered plungers which may be used.

Fig. 27 is a fragmentary longitudinal section of some of the disks (the fragment of the tumbler being in elevation) showing the gripping action between the disks and tumbler when a thief attempts to pick the lock.

Referring in detail to the drawings, Fig. 1 shows a conventional form of a movable part 1 within which is mounted a tumbler lock embodying my invention, by means of which this or any other desired movable part may be locked against movement and unlocked when desired. Referring to Figs. 3 and 11, my improved tumbler lock comprises a central shaft 2, the key end of which is formed into an enlarged end 3 and the opposite end of which is provided for a short part of its length with a non-circular portion 4, so that upon rotation of shaft 2 cam plate 3 will be rotated in one or the other direction. Fixed to cam plate 3 is a cam pin 5 by means of which a locking bolt (not shown) may be reciprocated in the usual manner. Closely adjacent the enlarged end 3, shaft 2 is provided with outstanding fins or ribs 6, over which ribs are forced by a force fit three disks a, b and c which form a head and which disks are circular in contour and are preferably stamped economically and in large numbers in suitable stamping machinery. This fixes head a, b, c rigidly in position on shaft 2 immediately back of the enlarged end 3. If desired, the head a, b, c, may be formed into a single piece instead of in the form of three disks, by welding, brazing or otherwise, or as a single piece, as desired. The shaft 2, enlarged end 3, and the fixed head or disks a, b and c constitute what I will refer to as the locking plug. The disks a, b and c will be referred to as the plug head.

Loosely mounted on shaft 2 and immediately to the rear of disk c is the barrel comprising disks d, e, f, g, h, i, j and k, which are generally similar to disks a, b and c except for the differences hereinafter pointed out. Disks d to k, as stated, are mounted upon shaft 2 with a certain amount of looseness so that for purposes more fully described earlier herein they may be moved edgewise rotationally a slight amount with relation to each other. Disks d to k each have a small hole therein through which, when these holes are brought into alignment, extends a rod 7 which is loosely riveted at its two ends to loosely hold these disks together upon shaft 2 to permit said slight edgewise rotational movement. There are also provided in the various disks as seen in Figs. 3 and 6 to 8, a plurality of registering holes through which extend the tumblers 8 and 9. In the form shown in Fig. 3, there are two of these tumblers in each of the combined registering holes, the two parts of each of these tumblers being of suitable different lengths for the desired locking purposes. Each of the tumblers is urged in a forward direction by a coiled

spring 10 in the bottom of each of the tumbler holes. The pin 7 is held by riveting or otherwise at one end to the disk d and at the other end to the disk k, so that the disks d to k are positioned together as a unit but more or less loosely as stated above. The disks a, b and c fixedly rotate together with the shaft 2 or, as stated, they may be formed of a single cylindrical block if desired.

Concentric with shaft 2 and extending inwardly over disks a to f, inclusive, is a cup-like shell 11 within which disks a, b and c are rotatable, but with relation to which disks d to k are stationary except for the slight movement referred to above. In order to mount disks d to k onto shell 11, disk e 15 is provided at diametrically opposite points with outstanding lugs 12 and 13 as seen in Figs. 3 and 11. Shell 11 at its inner end is provided at diametrically opposite points with bayonet slots 14 and 15. Lugs 12 and 13 are inserted into bayonet slots 14 and 15 and given a turn sufficient to carry them into the lateral extension of the bayonet slot. When thus positioned a spring-like ring member 16 having projections 17 and 18 see (Fig. 12) is inserted over disks f and g, with the projections 17 and 18 extending into the entrance portion of the bayonet slot in order to prevent backward movement from the laterally extending end of the bayonet slot of the lugs 12 and 13. The thickness of this spring member 16 in Fig. 12 is exaggerated for purposes of clarity, but it will be understood that the same is sufficiently thin to have enough resiliency to permit it to be removed should it be desired to disassemble these parts.

From the above it will be seen that except for the lugs 12 and 13 of disk e the disks a to f are of smaller diameter than disks h to k because of these first mentioned disks being within the shell 11. Disk g is also of smaller diameter than disks h to k because of receiving thereover the spring ring 16. The diameter of disks h to k is preferably substantially the same as the outer diameter of the shell 11 as seen in Fig. 3. As will be understood, in this type of lock the tumbler pins 8 and 9 (there being two of these pins in each of the tumbler holes) are longitudinally movable in the aligned holes in the various disks, and, as stated, are urged in one direction by the coil spring 10 in each hole. Fixed in any suitable manner within the inside front end of the cavity in shell 11 is a stop throw washer 19 against which a portion of the outer ends of the outer sections 9 of the tumblers slidably engage. The parting line or plane p in Fig. 3 is between the disks c and d.

The key 20 (see Figs. 3 and 10) is provided with suitable bittings 21 to accommodate the desired throw of the tumblers for the particular lock under consideration. As seen in Figs. 5 to 9, there are six of these tumblers in the lock now being described, except that the tumbler 8d is a dummy tumbler, by which is meant that it is not moved longitudinally when the key is inserted in place but its outer end is always in contact with the stop throw washer 19 except when being specially manipulated for enabling removal of the locking cylinder out of the locking mechanism body as later described.

From the above it will be seen that when the key 20 is inserted into the annular opening 22 and through a similar opening in the stop throw washer 19, the rear ends of the biting grooves will so strike the adjacent end of the tumbler pins 8 as to move each of the tumblers such distance as to bring the adjacent ends of tumbler pins 8 and 9 in registry with the parting

line *p*. The shaft 2, end *y* and rigidly mounted disks *a*, *b* and *c* (forming the plug head) will then upon rotation of the key be rotated inside of the shell 11, thus rotating the cam plate 3 fixed to the inner end of shaft 2, thus moving the cam pin 5 to throw the locking bolt into locked or unlocked position, depending upon the direction of movement. As stated above, the dummy pin 9^d is not moved longitudinally when the key is inserted in the lock, but the meeting ends of the two pins which together form the dummy pin always stand at the parting line so that when the other tumblers have been brought to the parting line by the key they together with the dummy pin will stand at the parting line and permit rotation as described above.

As explained above, the disks *d* to *k* are mounted sufficiently loosely with relation to shaft 2, pin 7 and shell 11 as to enable a certain amount of twisting movement of these disks with relation to each other so that when a would-be thief attempts to pick the lock these disks will rotate a slight distance with relation to each other and become cramped against the tumbler pins and hold such pins against manipulation necessary on the part of the thief to be able to bring all of the tumblers to the meeting line to operate the lock. This is true of the form of tumblers shown in Fig. 3, and even more so with the shouldered type of tumbler pins 8^c shown in Fig. 26. As will be understood, with such shouldered tumblers any rotational movement of the shaft 2 by the would-be thief would cause such rotational twisting of disks *d* to *k* with relation to each other as to bring the edge of one or the other of these disks beneath the shoulder of the shouldered locking pin, and thus prevent longitudinal movement of the locking pin and positively prevent the thief from being able to pick the lock.

As will be noted in Figs. 3, 8, 11, 13 and 14, the two innermost disks *j* and *k* are each provided with a peripheral notch which will be jointly referred to as 23. Extending into this notch is a lug or projection 24 integrally or otherwise formed at an adjacent position within the cylindrical opening in the locking mechanism body 1 within which the locking cylinder is mounted. The cam plate 3 is likewise formed with a peripheral notch 25 of a size substantially the same as notch 23, but normally positioned rotationally a slight distance laterally from notch 23 and lug 24 as seen in Fig. 4. This slight edgewise displacement of notch 25 with relation to lug 24 prevents the locking cylinder from being withdrawn from the cylindrical opening in the locking mechanism body 1 in the absence of special manipulation, which will now be explained.

As will be understood, when the key is inserted in the opening and the plug comprising the shaft 2, head 3 and disks *a*, *b* and *c* rotated, the cam plate 3 will also be rotated through any desired rotational distance (preferably 180°). Referring to Figs. 6 and 14, the stop throw washer 19 is formed with a punched out part or other projection 26 extending inwardly, there being one of these projections on one side of the axis of rotation and one of these projections on the opposite side of the axis of rotation in such position that the dummy pin 9^d will strike one of these projections 26 when the cam plate is at one limit of its movement and the other projection 26' (see Fig. 6) when the cam plate has rotated through approximately 180°.

When the dummy pin 9^d is against the one of

these two projections 26 or 26', which brings the notch 25 in cam plate 3 nearest into registry with the lug 24, notch 25 will still be the above mentioned distance out of registry with said lug 24 so that regardless of which end of its throw cam plate 3 may be, it will always keep notch 25 away from registry with lug 24 because of the free outer end of the dummy pin 9^d striking one or the other of these projections 26 and 26'. In order to bring notch 25 of cam plate 3 into registry with lug 24 to permit removal of the locking cylinder from the cylindrical opening in part 1 within which it is mounted, all that is necessary is to insert the key in its opening to the full distance and rotate shaft 2 and cam plate 3 into position to bring notch 25 as near as possible into registry with lug 24 and then insert a wire 27 or other suitable instrument through the opening in alignment with the outer end of dummy pin 9^d and push inwardly on this dummy pin until the dummy pin moves inwardly a sufficient distance to clear the inner end of projection 26.

The opening in disk *d* to which the dummy pin extends when thus pushed, is provided on one side with an elongated notch 28 (see Fig. 9) on that side, and of a sufficient length, to permit sufficient further rotation of the parts by rotation of the key to bring notch 25 in cam plate 3 into registry with lug 24, which will then permit cam plate 3 to pass lug 24 and permit the locking cylinder to be removed from the cylindrical opening in the locking mechanism body 1 in order to insert a different locking cylinder if desired. A new locking cylinder may be inserted in the opening in part 1 by a reverse operation, after which the locking cylinder will again be firmly locked in position until released in the manner just described. As seen in Fig. 14, when the wire 27 is pushed inwardly against the dummy pin to release the cylinder lock, the key being in position in the lock, all of the tumbler pins will have their meeting ends at the parting line but the dummy pin will be pushed slightly beyond the parting line and lateral movement thereof with relation to disk *d* will be permitted by the slot 28 in disk *d*.

A modified form of means for holding the locking cylinder in position in the locking mechanism body 1 but permitting removal thereof is shown in Figs. 15 and 16, in which a movable pin 29 is movably mounted in an appropriate radial opening formed in two or three of the disks referred to earlier herein other than disks *a*, *b* and *c*, the outer end 30 of this pin being of spherical shape and normally seating in a circumferential groove 31 which extends entirely around the circumference of the cylindrical hole within which the locking cylinder is mounted. At a suitable appropriate position in the shaft 2 and in circumferential alignment with the groove 31 is a semi-spherical depression 32 into which the inner end (which is also of spherical shape) of the pin 29 may drop when it comes into registry therewith. When the plug is rotated into position to cause the depression 32 to register with the inner end of pin 29, the locking cylinder may be pulled outwardly from the locking mechanism body by a straight longitudinal pull due to the fact that at this time the spherical shaped face 30 of the pin 31 will act as a cam with relation to the circumferential groove 31 and force pin 29 inwardly into recess 32 a distance to clear the outer end of the pin from circumferential groove 31, and allow the locking cylinder to be pulled

longitudinally out of the locking mechanism body. This permits of inspection, repairs or substitution of a new locking cylinder.

Positioned in an appropriate groove in shell 11' (which shell in this form is somewhat longer than the shell forms previously described) is a friction ring 33 which presses outwardly a desired amount against the inner face of the cylindrical opening in locking mechanism body 1 to normally hold the locking cylinder in place but yet permit it to be removed upon the application of a sufficient pull upon the key, or upon any other desired pulling means. This ring 33 bears against the inner surface of said hole with sufficient friction to prevent the locking cylinder from being rotated or removed too easily, but yet permitting removal by pulling upon the key or otherwise as referred to above. In this form there is only one parting line or plane, which is indicated at p and is the same as that described in connection with Fig. 3. This means that the locking cylinder may be removed in the manner stated above by the use of the normal key, and when requiring two parting lines or planes have a separate or master key.

In the form shown in Figs. 17 to 21, the locking cylinder is removable from the cylindrical opening in the locking mechanism body 1 through the use of a second or master key (which has different bittings from those of the normal key), this form of lock having two parting lines or planes, to-wit, one at p as in Fig. 3, and a second one at p'. This means that each of the tumblers will be made of three parts 8a, 9a and 9b, of such lengths as to permit rotation along the parting line p when the normal key is used (which at this time will not permit rotation about the parting line p'), and rotation about parting line p' when the master key with its different bittings is used. The purpose of the additional parting line p' is to enable rotation of the intermediate portion made up of the disks l, m, n (the plug head also rotating therewith) so as to bring the recess 41 (Fig. 21) opposite a projection 36 (see Fig. 20) so that the upstanding spring-like projection 37 may under its inwardly urged spring action move inwardly away from the circumferential groove 38 formed in the inner face of the cylindrical opening in the locking mechanism body 1. This, as will be understood, upon use of the master key permits the removal of the locking cylinder for inspection, repairs or renewal. The inside and outside projections 36 and 37 are carried by a spring-like ring 39 which seats in the circumferential groove 40 of the shell 11", it being understood that the projection 36 passes through the opening 35 in groove 40 of its shell.

It should be pointed out that when the master key is used to permit rotation at the parting line p', the tumblers will be in such position as to prevent rotation at the parting line p and hence at this time will cause the three intermediate disks l, m, n to rotate with the outer disks a, b and c, the intermediate disks l, m and n being provided with a depression 41 at the desired circumferential location in circumferential alignment with groove 40. When under action of the master key and rotation at the parting line p', the recess 41 is brought directly opposite the inner projection 36, the latter will under spring action move into recess 41, thus freeing the outer projection 37 from the circumferential groove 38 to permit the locking cylinder

to be removed longitudinally from the cylindrical hole in locking mechanism body 1. When the intermediate disks l, m and n are rotated upon reinsertion of the locking cylinder in the hole, so as to move recess 41 away from the inner projection 36, one or the other of the edges of recess 41 (depending upon the direction of rotation) will then move the outer projection 37 outwardly into groove 38 to lock the locking cylinder against removal from the locking mechanism body.

As seen in Figs. 15 and 17, two right-hand disks immediately inside of the cam plate 3 are formed with a recess 42 to receive the lug 43 projecting inwardly from the inner face of the locking mechanism body opening to locate the locking cylinder in proper position with relation to the other parts, to prevent rotational movement of the barrel of the locking cylinder and yet permit removal of the locking cylinder when pin 29 moves inwardly into depression 32 in Fig. 15, and when the outer projection 37 moves inwardly out of groove 38 in Fig. 17.

In Figs. 22 to 25, I have shown how a flat key may be modified to be used in the tumbler lock of my present invention. In this form the five tumblers and one dummy pin (making a total of six) are positioned closer together than in the previous forms, and the end of the otherwise flat key is formed at its upper and lower longitudinal edges with arcuate flanges 44, 45, 46 and 47 extending laterally a sufficient distance to engage each of the groups of three plungers, these flanges and intermediate portions being formed with the desired depth and size of bittings. Also in one or the other of the edges of the free end of the flat key may be formed one or more projections 48 to pass through a corresponding notch or notches in the outer end of the shell as will be understood. The free end of my modified form of flat key is shown in blank in Fig. 22, and after the bittings have been cut therein in Fig. 23. By this arrangement a substantially flat key may be used to operate my improved form of tumbler lock.

As will be understood from the above, the locking cylinder is made up of the plug, barrel and shell that together constitute the unit to throw the bolt into engagement with a locking mechanism body, or other similar part, to lock or unlock the parts as desired. The plug in Fig. 3 consists of the shaft 2, enlarged end y and three rigid disks a, b and c, the cam plate 3 being fixed at the inner end to the end of the shaft 2. The barrel is made up of the disks d to k loosely held together by pin 7 as shown at the right-hand side in Fig. 11. The tumblers are arranged parallel to each other and operate longitudinally in the openings in the barrel and the disks a, b and c. As stated, the disks a, b and c are rigidly fixed to the shaft 2, but the disks d to k are sufficiently loose with relation to each other and with relation to the shaft 2 as to be capable of a slight edgewise rotational movement to cause a cramping or gripping action on the tumblers to prevent longitudinal movement thereof should a thief attempt to pick the lock. The locking plug is rotatable in the barrel. The shell is fixed to the barrel and in turn is fixed to the locking mechanism body.

As will be understood, I have eliminated any slot, depression or projection in the outer end of the plug that might otherwise be available to a thief in attempting to pick the lock. Such thief would accordingly be unable to exert the

turning action to the plug that would be necessary in an attempt to pick the lock. If the thief should attempt to use a piece of tubing to turn the plug he would close the key opening and thus be unable to work on the tumblers. As the locking plug is all in one piece it can be made small and enable the use of a small key. The plug shaft will preferably be made of rustless iron or stainless steel to prevent rusting and enable smooth operation of the lock in all kinds of weather. The other inner parts that are away from the weather will preferably be made of brass or other non-corrodible metal. The disks may be stamped out thus enabling economical production, and eliminating the danger of a thief picking the lock as he could do with the old form of solid barrel.

Having now described my invention, I claim:

1. A tumbler lock having a rotatable plug, a barrel and a shell, the barrel comprising a plurality of disks arranged in parallel relation, said disks having alined openings to receive longitudinally movable tumblers, the disks being movable edgewise to cramp and grip the tumblers and prevent longitudinal movement thereof when a thief attempts to pick the lock. 20
2. A tumbler lock barrel comprising a plurality of disks having registering holes to receive tumblers, said disks being independently movable edgewise to cramp and grip the tumblers when a thief attempts to pick the lock. 25
3. In a tumbler lock, a rotatable plug, a relatively stationary barrel made up of a plurality of parallel disks receiving longitudinally movable tumblers, said disks being connected together by a longitudinal pin. 30
4. In a tumbler lock, a shell, a plug having a stem and being rotatable with relation to the shell when unlocked, a barrel secured to said shell and generally stationary relatively thereto, tumblers in said plug and barrel, said barrel comprising a plurality of parallel disks having a plurality of sets of openings to receive the stem and tumblers, said disks being connected together by a longitudinal pin. 35
5. In a tumbler lock, a shell, a plug having a stem and a head and being rotatable with relation to the shell when unlocked and non-rotatable with relation thereto when locked, a barrel comprising a plurality of relatively thin disks having alined axial openings to receive said stem, the stem being rotatable in the disks when the lock is unlocked and substantially non-rotatable with relation thereto when the lock is locked, cooperating tumblers longitudinally movable in the barrel disks and head, the disks being connected together by a pin, the barrel being connected to the shell to be substantially non-rotatable with relation thereto. 40
6. In a tumbler lock, a shell, a plug and a barrel, said barrel comprising a number of parallel disks, cooperating tumblers in the plug and barrel, one of said disks having means for securing it to the shell, and a pin connecting said disks together against separation longitudinally of the lock. 60
7. In a tumbler lock, a shell formed with a slot in its side wall, a plug, a barrel having a lug adapted to be seated in said slot, and means for removably holding the lug in the slot. 65
8. In a tumbler lock, a shell formed with a slot in its side wall, a plug, a barrel having a number of parallel disks, one of said disks having a lug adapted to be seated in said slot, and means for removably holding the lug in the slot. 70
9. In tumbler lock construction, a locking cylinder comprising a shell, a rotatable plug and a barrel, a locking mechanism body having an opening adapted to have the lock inserted longitudinally therewith, said barrel having a peripheral notch in one end portion thereof, a lug on said body extending into said notch, a cam plate fixed to said plug to rotate therewith and having a peripheral notch offset with relation to the first mentioned notch at all times during the normal operation of the lock to prevent the locking cylinder from being removed from the body, and means for enabling the two notches to be brought into registry so that the locking cylinder may be removed from said body by a longitudinal pull. 75
10. In a tumbler lock construction, a locking cylinder comprising a shell, a rotatable plug and a barrel, said plug having a head, said head and barrel carrying longitudinally movable tumblers therein, one of the tumblers being normally inactive and having its outer end always flush with the inner face of the shell during normal operation of the lock, a projection in the shell against which the outer end of the inactive tumbler strikes at the limit of one normal rotational movement of the plug, a locking mechanism body within which the locking cylinder is mounted, a lug on said body, said barrel having a notch receiving said lug, a cam plate fixed to said plug adjacent said lug and having a notch normally out of registry with the lug and first mentioned notch, the barrel having an opening in alignment with the inactive tumbler, said last mentioned opening adjacent the outer end of the barrel having a lateral recess, and means for pushing the inactive tumbler longitudinally to clear the shell projection and permit further rotation of the plug to bring the cam plate slot and the locking mechanism body lug into registry to enable removal of the locking cylinder from the locking mechanism body. 80
11. In a tumbler lock construction, a locking cylinder comprising a rotatable plug, a shell and a barrel, said plug and barrel having tumblers therein, one of said tumblers being always in a position to have its end in the parting plane between the adjacent faces of the plug and barrel during normal operation of the lock, a locking mechanism body having an opening within which said locking cylinder is mounted, a projection in said body, a recess in said barrel within which said projection is normally seated, means for normally holding said recess over said projection and means for releasing the barrel recess from said projection to permit removal of the locking cylinder from the locking mechanism body. 85
12. In locking mechanism, a locking cylinder comprising a rotatable plug, a shell and a barrel, a locking mechanism body having a lug, said barrel having a recess within which said lug is normally seated, a first means for normally preventing removal of the barrel from said lug, and a second means for freeing the barrel from said lug to enable removal of the locking cylinder from the locking mechanism body when desired. 90
13. In locking mechanism, a locking cylinder comprising a rotatable plug, a shell and a barrel, a locking mechanism body having a lug, said barrel having a recess within which said lug is normally seated, a first means for normally preventing removal of the barrel from said lug, and

a second means for freeing the barrel from said lug to enable removal of the locking cylinder from the locking mechanism body when desired, said first means comprising a cam plate on the plug and having a peripheral notch of a size to permit movement over the lug but normally out of registry therewith.

14. In locking mechanism, a locking cylinder comprising a rotatable plug, a shell and a barrel, a locking mechanism body having a lug, said barrel having a recess within which said lug is normally seated, a first means for normally preventing removal of the barrel from said lug, and a second means for freeing the barrel from said lug to enable removal of the locking cylinder from the locking mechanism body when desired, said first means comprising a cam plate on the plug and having a peripheral notch of a size to permit movement over the lug but normally out of registry therewith, said second means comprising a stop in the shell to limit rotational movement of the plug and cam plate, and a tumbler normally strikeable against said stop but removable away therefrom when desired to remove the locking cylinder from the body.

15. In locking mechanism, a tumbler locking cylinder comprising a shell, a rotatable plug and a barrel, the plug having a head, an intermediate rotatable portion, the plug head, the intermediate portion and the barrel each having a set of separate tumblers so as to provide two parting planes, one parting plane being between the adjacent faces of the plug head and the intermediate portion, and the other parting plane being between the adjacent faces of the intermediate portion and the barrel, a locking mechanism body, the intermediate portion having holding means coacting with the locking mechanism body to normally hold the locking cylinder in the locking mechanism body, said one parting plane being brought into operation upon use of a regular key, and said other parting plane being brought into operation upon the use of a master

key to release the said holding means from the locking mechanism body to permit withdrawal of the locking cylinder.

16. In locking mechanism, a tumbler locking cylinder comprising a shell, a rotatable plug and a barrel, a locking mechanism body having an opening within which the locking cylinder is normally mounted, the locking cylinder and the locking mechanism body having coacting means preventing withdrawal of the locking cylinder during normal operation of the locking mechanism, and manual means operable from the front face of the locking cylinder for releasing said coacting means to enable withdrawal of the locking cylinder from the locking mechanism body.

17. In locking mechanism, a tumbler locking cylinder comprising a shell, a rotatable plug and a barrel, a locking mechanism body having an opening within which the locking cylinder is normally secured, the walls of said opening having a recess, a pin transversely movable in said barrel and having its outer end normally seated in said recess, a recess in the side of the rotatable plug, said plug being rotatable by a key to bring the recess in the plug into registry with the pin to permit the pin to move into the recess in the plug to enable withdrawal of the locking cylinder from the locking mechanism body.

18. In combination in a tumbler lock, a shell having an opening in its front face, a plug and a barrel, tumblers longitudinally movable in the plug and barrel, the plug being rotatable in the shell and barrel, a key of the flat type having on its front end laterally extending arcuate flanges, bitings in the forward end of said key and flanges, the forward end of the plug being positioned within the opening in the shell and radially spaced from the edges thereof to form an annular opening, the arcuate flanges of the key being insertable into said annular opening to operate the tumblers.

HARRY F. GEORGE.
